PACKAGED ARTICLE

Harold Rosen, Muskegon, Mich.

Application November 15, 1940, Serial No. 365,753

10 Claims. (Cl. 206—56)

This invention relates to packaged articles, and more particularly to the packaging and dispensing of articles in stick form.

In handling articles in stick form, and particularly articles composed of plastic solids, such as crayons, lubricant, cosmetics, etc., it has been common practice to package such articles in rigid permanent containers from which they are dispensed by moving the article in the container until one end is exposed, or by wrapping the article in paper, thin metal, foil, or the like, which can be stripped from the stick to expose successive portions as the stick is consumed.

The first of these methods is extremely expensive and is unsatisfactory because it is impossible to see how much of the unconsumed stick remains, and special means must be provided to advance the stick in its container. The second method does not provide a good support for the stick material and no practical method has been devised to control the length of stick being exposed; usually also a knife or other sharp instrument is required to strip the wrapper from the stick.

It is one of the objects of the present invention to provide a packaged article in the form of stick material enclosed by a relatively thin integral casing, which can be severed from the article in the form of a relatively narrow spiral strip. It is a further object of the invention to provide means by which the length of stick exposed can be accurately controlled at all times.

According to one feature of the invention a collar is provided carrying a small blade which severs the casing from the material as the collar is turned about the encased stick.

Another object of the invention is to provide a packaged article of the type referred to, in which the end of the casing is closed by a cap, which when replaced upon the stick automatically severs so much of the casing as to expose a predetermined length of the stick when the cap is again removed.

Still another object of the invention is to provide a packaged article of the type referred to, in which the casing is cut from the stick material in the form of a narrow spirally extending strip.

The above and other objects, advantages and desirable features of the invention will be apparent from the following description when read in connection with the accompanying drawing, in which:

Figure 1 is a side elevation of a packaged article embodying the invention;

Fig. 2 is a perspective view of the cap of Figure 1;

Fig. 3 is a side elevation of the article with the cap removed;

Fig. 4 is a section on the line 4—4 of Fig. 1;

Fig. 5 is a side elevation of an alternative construction;

Fig. 6 is a perspective view of the collar of Fig. 5;

Fig. 7 is a view similar to Fig. 5, showing a modified form of package which is preformed to provide a thread throughout its length to engage the thread upon the cap shown in Fig. 2 or the collar shown in Fig. 6;

Fig. 8 is a perspective view of an alternative form of collar; and

Fig. 9 is a side elevation of a closure cap.

The invention is particularly advantageous for the packaging and dispensing of waxlike materials such as stick lubricants, lip stick, eyebrow pencils, crayons, soaps, and similar solids which are most conveniently employed in stick form. Such articles may be enclosed in a relatively thin casing formed of metal, foil, paper, plastic lacquers, or like materials which can be cut. One method of inserting the stick article in a casing of this type is more particularly disclosed and claimed in my co-pending application, Serial No. 365,752, filed November 15, 1940, although other methods can be used if desired.

As shown in Figs. 1 to 4, the article comprises a stick 10 of waxlike material enclosed in a tightly fitting casing 12, which is relatively thin. The casing may be an open tube or may be closed at one end permanently and is adapted to have the opposite end at which the stick is being used closed to cover the stick 10 by means of a cap 14. The cap includes a collar portion 16, formed adjacent its lower end with a screw thread 18, rolled or otherwise formed therein and knurled or milled portions 17 and 19 to facilitate its rotation, and is closed at its upper end by an end closure portion 20. The cap is adapted to be placed over the end of the casing and advanced by turning it so that the screw thread 18 will press a complementary thread in the side wall of the casing and in the stick as indicated at 22 in Fig. 3. This is readily accomplished with plastic solid materials, similar to those enumerated, enclosed within metal, foil, or similar materials which can readily be deformed by the thread 18 in the cap. Especially suitable materials are lead or aluminum foil, or foils composed of mixtures of aluminum, lead and zinc, or for uses where lead is not permissible, zinc or aluminum

alone. Other familiar alloys used for the manufacture of tubes of this character may be employed, as well as many of the plastic lacquers which remain relatively soft when dry.

Where the material of which the stick is composed is too hard to permit pressing a thread into it, the casing above will receive the thread impression and serve to advance the cap as it is rotated about the encased stick.

The invention contemplates that the cap 16 will be provided with a short blade member projecting from the inner wall of the cap to a sufficient depth to cut through the casing 12 as the cap 14 is rotated. In the embodiment of the invention shown in the accompanying drawing, the collar portion 16 of the cap 14 is cut adjacent the lower end thereof to form the thin blade member 26, which is pressed inwardly to form the opening 24. The blade member remains attached to the collar at its lower edge, and extends upwardly and inwardly therefrom at an acute angle to a depth sufficient to penetrate the casing 12 and of a depth sufficient to sever a strip of the casing of approximately the width of the thread 18, so that as the cap is rotated upon the stick, the casing will be cut away as the cap advances along the stick.

As the collar is applied to the stick, and rotated to bring the top of the cap snugly against the end of the stick, the blade 26 will cut into the upper end of the casing and sever it in the form of a relatively narrow spirally extending strip. Due to the angle of the blade, it will at the same time force the strip out through the opening 24, as shown in Figs. 1 and 4, so that the protruding end of the strip may readily be torn off. The collar may be screwed on until the end closure 20 thereof engages the top of the stick, the distance between the blade 26 and the end closure determining the amount of the stick which will be exposed upon subsequent removal of the cap. Thus at no time is the newly exposed portion of the stick exposed until the cap is removed for use of the stick.

Figs. 5 and 6 illustrate an alternative construction which is similar in many respects to the construction of Figs. 1 to 4, and in which the corresponding parts are indicated by the same reference numerals. In this construction, an annular collar 28 formed with a screw thread 30 and knurled bands 29 is adapted to be rotated about the casing 12 to form the threads upon the body of the casing in much the same manner as the cap 14 of Fig. 1 operates. The collar is formed with a blade portion 32, which may be formed by slitting the upper edge of the collar axially and bending in a portion thereof at one side of the slit to provide a blade along an acute angle to the collar. As the collar is turned down over the casing 12 the blade 32 will cut the casing from the stick 10 in the form of a narrow spirally extending strip, and will at the same time guide the strip away from the stick so that it may be torn off easily to expose any desired amount of stick. While the upper end of the collar is open in this construction to leave the end of the stick exposed, a cap 34, as shown in Fig. 9, may be provided to slip over the upper end of the stick and to fit essentially over either merely the exposed end of the stick or both the exposed end of the stick and the collar to enclose the stick.

Fig. 7 illustrates a modification of the construction of Fig. 5 and parts therein corresponding to like parts in Fig. 5 have been given the same reference numerals. In this construction,

the casing itself is preformed with a screw thread 36, complementary to the thread 30 of collar 28, so that the collar may be rotated about the casing and advanced longitudinally without the necessity of forming a thread by the rotation of the cap. This alternative form is particularly suitable where the character of either the encased stick or the casing material employed does not readily lend itself to deformation by the cap thread. As the collar is rotated about the threaded casing the blade 32 on the collar cuts the casing away from the stick in the same manner as in the construction shown in Fig. 5.

Fig. 8 illustrates another form of collar which may be used in place of the collars of Figs. 5, 6 and 7, or of the cap of Figure 1. As shown, this collar comprises an annular sleeve 38, knurled with the knurling 39. The blade 40 in this device is formed so that it will, as the collar is turned, make a helical cut in the casing and thus advance the collar axially of the casing simultaneously cutting the casing into strip form and forcing the strip outside of the collar. This form of collar differs principally from the other constructions shown in the elimination of the threaded portion of the collar body.

While several embodiments of the invention have been shown and described, it will be understood that these are illustrative only and are not intended as a definition of the scope of the invention, reference being made for that purpose to the appended claims.

What is claimed is:

1. A packaged article comprising an elongated stick of material, a thin-walled casing fitting tightly over said stick so as to be held against axial movement relative thereto, a collar having a substantially cylindrical wall portion surrounding and rotatably and longitudinally movable over said casing, and a blade member projecting radially inwardly from said wall portion of the collar to cut the casing away from the periphery of the stick in a relatively narrow strip as the collar is turned.

2. A packaged article comprising an elongated stick of material, a thin-walled casing fitting tightly over said stick so as to be held against axial movement relative thereto, and a collar having a substantially cylindrical wall portion adapted to fit over the casing and formed with a blade member pressed inward from said wall portion of the collar to cut the casing away from the periphery of the stick in a relatively narrow strip as the collar is turned on the casing.

3. A packaged article comprising an elongated stick of material, a thin-walled casing fitting tightly over said stick so as to be held against axial movement relative thereto, a collar having a substantially cylindrical wall portion adapted to fit over the casing and formed with a screw thread engaging the casing to advance the collar along the casing as it is turned, and a blade projecting inwardly from said wall portion of the collar to cut the casing away from the periphery of the stick in the form of a relatively narrow strip as the collar is threaded onto the casing.

4. A packaged article comprising an elongated stick of material, a thin-walled casing fitting tightly over said stick so as to be held against axial movement relative thereto, said stick and casing being shaped to form a screw thread on their outer surface, a collar formed with a screw thread to be threaded onto the casing, and a blade carried by the collar to cut the casing away

from the periphery of the stick as the collar is screwed over the casing.

5. A packaged article comprising an elongated stick of deformable solid material, a thin pliable casing fitting closely over the stick, a collar formed with a screw thread having an internal peak diameter less than the external diameter of the casing to press the casing into the form of a complementary screw thread and to advance the collar along the casing as it is turned, and a blade carried by the collar to cut the casing from the stick in the form of a relatively narrow spirally extending strip as the collar is threaded onto the casing.

6. A packaged article comprising an elongated stick of deformable solid material, a casing of metal foil fitting closely over the stick, a collar formed with a screw thread having an internal peak diameter less than the external diameter of the casing to press the casing into the form of a complementary screw thread and to advance the collar along the casing as it is turned, and a blade carried by the collar to cut the casing from the stick in the form of a relatively narrow spirally extending strip as the collar is threaded onto the casing.

7. A packaged article comprising an elongated stick of material, a thin-walled casing fitting closely over said stick so as to be held against axial movement relative thereto, a collar rotatable and longitudinally movable over said casing, and a thin metal blade portion secured at its lower end to the collar and extending upwardly and inwardly therefrom at an angle to sever said cover from the periphery of the stick in the form of a narrow spiral strip and to guide the severed strip away from the stick.

8. A packaged article comprising an elongated stick of material, a thin-walled casing fitting closely over said stick, a cap fitting over the 40 end of the stick having an annular collar portion

to fit over the casing, and an end closure portion to rest on the end of the stick, said cap being adapted for simultaneous rotational and lengthwise movement upon the stick, the collar portion of the cap having an opening therein spaced from the end closure and a blade member carried by the cap projecting inwardly from said opening to cut the casing from the stick in the form of a narrow spirally extending strip as the collar is turned onto the stick.

9. A packaged article comprising an elongated stick of material, a thin-walled casing fitting closely over said stick, a cap fitting over the end of the stick having an annular collar portion to fit over the casing, and an end closure portion to rest on the end of the stick, said cap being adapted for simultaneous rotational and lengthwise movement upon the stick, the collar portion of the cap having an opening therein spaced from the end of the closure, and a thin blade member projecting inwardly and upwardly from the lower portion of said opening to cut the casing from the stick in the form of a narrow strip and to guide said strip out through the opening as the cap is turned onto the casing.

10. A packaged article comprising an elongated stick of material, a thin-walled casing fitting closely over said stick, a cap fitting over the end of the stick having a collar portion formed with a screw thread at its lower end and a closure portion at the upper end of the collar portion, said screw thread engaging the casing to advance the cap longitudinally thereof until the end of the stick strikes the closure portion as the cap is turned, and a blade carried by the cap, spaced from the closure portion thereof to cut the casing from the stick in the form of a narrow spirally extending strip as the cap is turned.

HAROLD ROSEN.
